A. S. Patterson,

Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL TORPEDO.

1,403,490.

Specification of Letters Patent. Patented Jan. 17, 1922.

Application filed June 21, 1921. Serial No. 479,238.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal Torpedoes, of which the following is a specification, reference being had therein to the accompanying drawing.

10 This invention relates to improvements in railway signal torpedoes, and more particularly to a torpedo wherein the explosive is contained within a wrapper and is then provided with an open-ended protecting casing, 15 and a rail-engaging or attaching member.

In the torpedo of my invention, the explosive wrapper and container are preferably made of paper or fibre and the rail-attaching member is of suitable metal. The cross- 20 sectional area of the explosive and wrapper is approximately the same as the cross-sectional area of the interior of the protective casing, and for this reason the explosive and its covering wrapper fit tightly in the casing, and more especially so because the rail-engaging member is also carried within the 25 casing.

In manufacturing a torpedo of the nature described above, I have found that considerable trouble and time is expended in fitting the explosive to the casing, because the fit between the two is very snug. To overcome this objection to a torpedo of this construction, I have invented and employ a 30 novel construction hereinafter to be described.

The object of my invention is to provide a novel means of wrapping a railway signal torpedo explosive so as to enable its being 35 easily inserted within a snugly fitting case.

Another object of my invention is to provide a railway signal torpedo comprising a wrapped explosive and a rail-engaging member carried within a case of a novel construction, so that it will be cheap of manufacture.

A still further object of my invention is to provide a railway signal torpedo comprising a wrapped torpedo and rail-engaging member carried in a case, the torpedo being of a novel construction, whereby when the explosive, together with its wrapper and rail-engaging member, are inserted in the case, the case will be flat upon its bottom.

Other and further objects of my invention will appear in the following specification and drawings, in which:

Figure 1 is a perspective view of a torpedo embodying my invention.

Fig. 2 is a perspective view of the several 60 parts of my improved torpedo, the parts being shown in unassembled relation.

Fig. 3 is an exaggerated longitudinal vertical sectional view of Fig. 1.

Fig. 4 is an exaggerated transverse vertical sectional view taken on the line 4—4 of Fig. 3.

Fig. 5 is a perspective view of a torpedo embodying a modified form of the explosive tablet.

Fig. 6 is a perspective view showing the modified form of explosive tablet having a concaved lower face.

Fig. 7 is an enlarged transverse vertical sectional view of a torpedo embodying the 75 modified form of the explosive tablet.

Fig. 8 is a detailed perspective view showing the longitudinal folds in the extended ends of the wrapper, as applied to the concaved form of the explosive tablet.

Referring now to the drawings in which like parts are designated by similar reference numerals throughout the specification and drawings, 1 represents an explosive, preferably of tablet form and carried within the several folds 2, of a paper or fiber wrapping 3, which has the outwardly extending ends 4 and 5 beyond the explosive.

To safeguard against dampness penetrating to the explosive 1 and thereby injuring 90 the same, the wrapper 3 is coated on its inner side with a water-proofing cement 6, or its equivalent.

As is clearly seen in Figs. 2 and 4, I have crimped or mashed inwardly the side walls 95 7 of the extending ends 4 and 5 of the wrapper to make longitudinal folds 8, whereby these extended ends are made of less width than the explosive 1.

The open ended case 9 whose cross-sectional interior is approximately the same as the cross-sectional area of the torpedo explosive and its wrapper, together with a rail-attaching member or strap 10, complete the component parts of my torpedo.

It will be readily understood that the ends 4 and 5 are folded inwardly upon the explosive, as shown in Fig. 3, and the strap 10

placed within the case 9, before the explosive and its wrapper are placed or slid inwardly through one of the open ends 11 of the case.

5 By crimping or mashing the side walls of the extending ends of the explosive wrapper and thus reducing their width, I find that much time and labor are saved in inserting the explosive into its snugly fitting 10 case. It will also be apparent that it is quite desirable that the explosive fits the case snugly, so that the rail-attaching member or strap 10 will be firmly clamped or held in its place.

15 Although I have shown in the drawings the rail attaching member in the form of a strap, preferably lead, adapted to be bent around the rail-head of a railway rail when the torpedo is in operative position, I desire 20 it to be understood that I do not limit myself to this form of rail-attaching means, and that a spring clip form of rail-engaging member or other similar rail-attaching means well-known to the art can be employed without departing from the spirit 25 of my invention.

Also a different form of explosive than the tablet, shown in the drawings, and described in the specification, can be used 30 without departing from the spirit of my invention. If it is desired, an explosive in its powdered form can be used.

Referring now to Figs. 5, 6 and 7, these figures show a modified form of the explosive tablet and its advantage in a torpedo where the explosive is wrapped and then inserted in an open ended container or case, which case also carries the rail-engaging member.

40 In these figures of the drawings, 12 represents an explosive tablet having a concaved lower face 13. In my modified form of torpedo, the explosive is similarly wrapped as in the preferred form 2, in a 45 paper or fiber wrapping 3, which has the outwardly extending ends 4, the side walls 7 of which are crimped or mashed inwardly to make the longitudinal bellows-like folds 8, whereby these extended ends are made of 50 less width than the explosive tablet 12.

Referring now particularly to Fig. 7, it will be seen that when the explosive tablet is wrapped within the fibrous covering 3, and the extended ends of the covering are 55 crimped or mashed as described and the extended ends then bent inwardly that the said extended ends lie wholly within the concaved lower face 13 of the explosive tablet. It will further be observed that said explosive tablet, with its fibrous covering arranged as described, is inserted within the open ended case 9, whose cross-sectional interior is approximately the same as the cross-sectional area of the explosive and its 60 wrapper. The case 9 also carries the rail-

engaging strap or member 10 and when the explosive tablet is inserted in the case, this member 10 lies within the concaved lower face of the explosive between the inwardly folded ends 4 of the fibrous wrapping 3 and 70 the case 9, as clearly appears in Fig. 7.

With this construction, I have provided a wrapped explosive tablet provided with a rail-engaging member carried within an open ended case, with the improved result 75 of insuring a perfectly flat bottom to the outer torpedo case. The advantage of this construction is that a complete torpedo having a case with a flat bottom is presented for engagement with the rail-head of a rail-road rail, as is not the case in the construction shown and described in Figs. 1 and 4 of the drawings.

To complete the torpedoes of both the preferred and modified forms and to doubly 85 safeguard the explosives from dampness, the torpedo can be given a waterproof bath.

From the foregoing, it will be seen that I have provided a novel means of wrapping an explosive tablet to provide for its easy 90 insertion, together with its rail-engaging member into a snugly fitting case and have thereby simplified and cheapened the manufacture of torpedoes of this character.

It will also be seen that I have additionally provided a novel means of constructing a torpedo which comprises an explosive carried within a wrapper and provided with a case which carries both the explosive and its rail-engaging member in such a manner that 100 the bottom of the case is flat.

Having thus described my invention, what I claim and desire to secure by Letters Patent is:

1. A railway signal torpedo comprising 105 an explosive having a wrapper with extended ends, the extended ends of the wrapper less in width than the explosive, a rail-engaging member, and a case carrying the explosive and the rail-engaging member 110 therein.

2. A railway signal torpedo comprising an explosive carried within the several folds of a wrapper, the wrapper provided with extended ends beyond the explosive, the side 115 walls of the extended ends of the wrapper crimped inwardly to reduce the width of the ends, the extended ends bent inwardly upon the explosive, a rail-engaging member, and a case carrying the rail-engaging member 120 and the explosive therein.

3. A railway signal torpedo comprising an explosive wrapped within the several folds of a fibrous sheet, the fibrous sheet having extended ends beyond the explosive 125 adapted to be folded inwardly thereupon, the side walls of the extended ends of the sheet mashed inwardly throughout their length to reduce the width of the ends, a rail-engaging member, and an open ended 130

case adapted to receive the explosive and the rail-engaging member therein, for the purpose described.

4. A railway signal torpedo comprising an explosive wrapper within the several folds of a fibrous sheet, the fibrous sheet having extended ends beyond the explosive, the side walls of the extended ends of the sheet crimped inwardly to form longitudinal 10 folds throughout the length of the ends, a rail-engaging member, and an open ended case adapted to receive the explosive and rail-engaging member, for the purpose described.
- 15 5. A railway signal torpedo comprising an explosive having a concaved face and provided with a wrapper with extended ends, a rail-engaging member, a case carrying the explosive and rail-engaging member 20 therein, and the extended ends of the wrapper folded inwardly upon the concaved face of the explosive, for the purpose described.
- 25 6. A railway signal torpedo comprising an explosive having a concaved face and provided with a wrapper with extended ends, the extended ends of the wrapper less in width than the explosive, a rail-engaging member and a case carrying the explosive and rail-engaging member therein.
- 30 7. A railway signal torpedo comprising an explosive with a concaved face having a wrapper with extended ends, the extended ends of the wrapper folded inwardly, a rail-engaging member, a case carrying the ex-

plosive and rail-engaging member therein, whereby when the explosive is inserted in the case the inwardly folded ends of the wrapper and rail-engaging member lie wholly within the concaved face of the explosive, for the purpose described.

40 8. A railway signal torpedo comprising an explosive having a wrapper with extended ends, the extended ends of the wrapper less in width than the explosive and folded inwardly, a rail-engaging member, a 45 case carrying the explosive and rail-engaging member therein, and the explosive provided with a concaved face whereby when it is inserted in the case the inwardly folded ends of the wrapper and engaging member 50 lie wholly within the concaved face of the explosive, for the purpose described.

9. A railway signal torpedo comprising an explosive having a concaved face, a wrapper for the explosive provided with extended 55 ends, and the extended ends of the wrapper folded inwardly upon the concaved face of the explosive for the purpose described.

10. A railway signal torpedo comprising an explosive having a wrapper with ex- 60 tended ends, the extended ends of the wrapper folded inwardly upon the explosive, a rail-engaging member, and a case carrying the explosive and the rail-engaging member therein.

65 In testimony whereof I hereunto affix my signature.

FRANK DUTCHER.
